UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

DRILLING APPARATUS

Application filed July 27, 1928. Serial No. 295,786.

This invention relates to drilling apparatus and more particularly to a drilling apparatus of the self-propelled type which is adapted to use in the mines and adapted to 5 operate from the mine trackway.

An object of this invention is to provide an improved drilling apparatus. Another object is to provide an improved self-propelled drilling apparatus especially adapted 10 to use in mines and adapted to operate from the mine trackway. A further object is to provide an improved drilling apparatus having improved adjusting and supporting means for the drilling tool whereby the latter may be positioned relative to the work 15 with facility and expeditiously. Yet another object is to provide an improved coal drill especially adapted to use in drilling "shot" holes in the working face of the coal. A further object is to provide an improved self- 20 propelled wheeled support and improved adjustable supporting means for a drilling tool together with improved driving connections therefor whereby an exceedingly compact and 25 easily adjustable drilling apparatus is obtained. These and other objects of the invention will subsequently more fully appear.

In the accompanying drawings there is shown for purposes of illustration one form 30 which the invention may assume in practice.

In these drawings,—

Fig. 1 is a side elevational view of the improved drilling apparatus, the drilling tool being shown adjusted into a plurality of positions.

Fig. 2 is an end elevational view of the drilling apparatus shown in Fig. 1 with the drilling tool omitted to facilitate illustration.

Fig. 3 is a plan view of the drilling apparatus shown in Fig. 1, the drilling tool being adjusted into a plurality of positions.

Fig. 4 is a fragmentary sectional view taken substantially on line 4—4 of Fig. 3.

Fig. 5 is a transverse vertical sectional view partially in elevation taken substantially on line 5—5 of Fig. 1.

Fig. 6 is a detail sectional view taken on line 6—6 of Fig. 5.

Fig. 7 is a central longitudinally extend-

ing vertical sectional view taken substantially on line 7—7 of Fig. 3 and illustrating details of construction of the drilling tool per se.

Fig. 8 is a horizontal sectional view taken on line 8—8 of Fig. 5 and illustrating details of construction of the cable reel.

Fig. 9 is a transverse vertical sectional view taken on line 9—9 of Fig. 8.

In this illustrative construction there is 60 shown a drilling apparatus generally comprising a drilling tool generally designated 1 supported on a self-propelled wheeled truck 2 by means of improved adjustable supporting means generally designated 3. As illustrated, the wheeled truck 2 comprises a truck frame 4 having side frame members 5 connected together at their ends by transverse bearing members 6 in which the front and rear truck axles 7 and 8 are respectively journaled. Fixed to these axles 7 and 8 are the 65 usual truck wheels 9 adapted to run along a usual mine trackway 10. As shown the bearing members 6 of the truck frame each have formed integral therewith a combined 70 bumper and coupling member 11 by means of which the truck may be connected to a locomotive to permit the drilling apparatus to be moved about the mine independently of its own power. Now referring to the improved 75 adjustable supporting means it will be observed that the side frame members 5 of the truck have formed thereon, intermediate the wheel axles, bearing members 12 carrying usual bearing sleeves 13 (see Fig. 5). Rotatably mounted in the bearing sleeves 13 for 80 tilting movement about a transverse horizontal axis is a housing or casing 14 having lateral trunnions 15 projecting within the bearing sleeves and forming bearings for the casing 85 on the truck. The mechanism for tilting or rocking the casing 14 within its bearings relative to the truck frame will hereinafter be described. Rotatably mounted on the casing 14 about an axis perpendicular to the axis of 90 tilting movement thereof is an upstanding tubular column or standard 16. Fixed to the column 16 at its upper end as by screws 17 is a housing or casing 18. The housing 18, as 95 shown in Fig. 4, has formed integral there- 100

with a rearwardly projecting support or arm 19 which has rigidly secured thereto at its extreme rearward end, as by screws 20, a motor 21. In this instance, arranged in axial 5 alinement with the motor and rotatably mounted on the frame 18 is a forwardly projecting boom or tubular supporting arm 22 which carries at its extreme outer end the drilling tool 1. The drilling tool 1 may be 10 of the same general type as that described in my copending applications, Ser. No. 200,826, filed June 23, 1927 and Ser. No. 255,754, filed Feb. 20, 1928, and a copending application of 15 one Richard E. Murphy, Ser. No. 274,821, filed May 3, 1928, now matured into Patent No. 1,848,376, patented March 8, 1932.

Referring more particularly to the driving connections between the motor and the drilling tool 1 it will be observed from Fig. 4 20 that the armature shaft 23 of the motor 21, which herein may be of the reversible electric type, is journaled at its forward end in ball bearings 24 suitably carried within the front motor head. This armature shaft 23 has 25 fixed thereto by a key 25 a coupling member 26 having internal keys 27 cooperating with keyways 28 formed on the periphery of a shaft 29 alined with the motor shaft and journaled in ball bearings 30 suitably supported 30 within the housing or casing 18. The shaft 29 has fixed thereto by a key 31 a bevel pinion 32 which meshes with a bevel gear 33, supported in a manner to be later described, which in turn meshes with a bevel pinion 34 35 fixed at 35 to a shaft 36 arranged in axial alinement with the motor shaft. The shaft 36 is herein the main driving shaft for the drilling tool 1 and, as shown in Figs. 4 and 7, is journaled at its opposite ends in ball bearings 37 and 38, the ball bearing 37 being supported within the rear end of the adjustable tubular supporting arm or boom 22, while the bearing 38 is supported by a frame or swivel bearing bracket 39 secured to the 40 outer end of the arm 22 as by screws 40. The drilling tool 1 is swiveled on the bearing bracket 39 as will later be described. In this instance the tubular supporting arm 22 surrounds the shaft 36 and is journaled at its 45 rear end for rotation about its longitudinal axis in spaced alined ball bearings 41 and 42 suitably carried by the housing or casing 18. As shown in Fig. 7 the outer end of the main drive shaft 36 has fixed thereto at 43 a bevel pinion 44 meshing with a larger bevel ring gear 45. The bevel ring gear 45 is rotatable about an axis perpendicular to the axis of the driving shaft 36 and is journaled on a ball bearing 46 suitably supported by a bearing 50 bracket 47 and a swivel plate 48. The swivel plate 48 is rigidly secured by screws 49 to the bearing bracket 47. The swivel plate 48 is herein rotatably mounted in a bore 50 arranged concentrically with the bevel gear 45 55 and formed within the bracket 39 and is pro- vided with a peripheral groove 51 with which a clamp or set screw 52 is adapted to engage to clamp the swivel plate 48 in its different adjusted positions rigidly to the bracket 39. As illustrated the bevel ring gear 45 meshes 70 with a bevel gear 53 fixed at 54 to a shaft 55 in a plane with main driving shaft 36. The shaft 55 is journaled in ball bearings 56 carried by the bearing bracket 47. Also fixed to the shaft 55 is a spur gear 57 while formed integral with the opposite end of the shaft 55 is a spur gear 58. The gears 57 and 58 mesh respectively with spur gears 59 and 60, the spur gears 59 and 60 constituting the driving elements for the tool rotating and feeding mechanism and which are adapted to effect rotation and feeding of a drill bit 61 through friction clutches 62 and 63 and a differential screw mechanism 64. As this specific feeding and rotation mechanism for the cutting bit 61 is clearly described in the copending applications mentioned above further description of the same is herein submitted to be unnecessary other than to state that the drill bit is adapted to be fed forwardly at a slow cutting 80 speed and retracted at a relatively high speed while the same is continuously rapidly rotated. From the foregoing description it is evident that the drilling tool 1 may be swiveled on the outer end of the supporting arm 22 and rigidly locked in any of its adjusted 85 positions. The mechanism for effecting rotation of the boom or tubular supporting arm 22 within its bearings 41 and 42 carried by the housing 18 herein comprises a worm gear 65 (see Fig. 4) fixed by keys 66 to the supporting arm 22 intermediate the supporting bearings. As illustrated, meshing with the worm gear 65 is a worm 67 having suitable operating handles 68 disposed at the opposite ends of the worm. This rotation mechanism for the supporting boom is clearly described in my copending application Ser. No. 255,754, mentioned above. It is accordingly 90 evident that the supporting arm or boom upon rotation of the worm gearing 67, 65 may be rotated about its longitudinal axis relative to the housing 18 and as a result the drilling tool 2 may be swung bodily about the axis of the supporting arm. As this worm gearing is of the self locking type the boom is rigidly locked against rotation after such adjustment. 95

The driving connections between the motor and the truck wheels will now be described. As mentioned above the motor shaft drives the bevel pinion 32 which meshes with the bevel gear 33. This bevel gear is keyed at 69 to a vertical shaft 70 arranged concentrically with and extending through the upstanding column of standard 16 as clearly shown 100 in Fig. 5. The opposite ends of the shaft 70 are journaled in ball bearings 71 and 72 suitably supported within the housing 18 and a frame member 73 respectively. This frame 73 is fixed by screws 74 to the tiltable 105

housing 14. As shown the frame member 73 has an upstanding sleeve portion 75 projecting upwardly through the column 16 and surrounding the shaft 70.

6 The upstanding column or standard 16 is rotatably mounted on the sleeve portion 75 of the frame 73 about the axis of the shaft 70 on bearing sleeves 76 interposed between the standard 16 and the sleeve portion 75. 70
 10 Downward axial thrust of the column 16 is received by a ball thrust bearing 77 interposed between the lower surface of the bottom bearing sleeve 76 and an annular shoulder formed on the frame 73, the ball thrust bearing 77 surrounding the sleeve portion 75 of the frame. Again referring to the driving connections between the motor and the truck wheels it will be observed that the shaft 70 has keyed thereto at 78 a bevel pinion 79 which constantly meshes with reverse bevel gears 80 and 81. The bevel gears 80 and 81 are respectively connectible to a transverse horizontal shaft 82 by means of friction clutch devices 83 and 84 respectively. The 85 shaft 82 is arranged coaxially with and extends through the supporting trunnions 15 for the tiltable frame 14 and is journaled in ball bearings 85 suitably supported within the casing 14. The friction clutch devices 30 83 and 84 have suitable shipper mechanism including a shipper member 86 slidably axially in opposite directions relative to the shaft 82 and includes a suitable operating lever 87 pivotally mounted on the casing 14 (see Fig. 3). From the foregoing it is evident that when one or the other of the friction clutch devices 83 and 84 is applied the shaft 82 may be driven from the motor 21 in one direction or the other. Fixed by keys 88 to the opposite ends of the shaft 82 are chain sprockets 89 and 90. The sprocket 89 is connected by a chain and sprocket connection 91 with the front truck axle 7 while the sprocket 90 is connected by a similar chain and sprocket connection 92 with the rear truck axle. 95

As pointed out above the tubular supporting column 16 is rotatably mounted about the axis of the shaft 70 and the means for holding this column in its different adjusted positions herein comprises a set screw 93 having a pivoted operating handle 94 and engaging a serrated clamping member 95. This clamping member is engageable with the outer periphery of a drum herein formed integral with the supporting column 16 at its lower end. It will thus be seen that the supporting column 16 may be rotated about a substantially vertical axis relative to the truck frame and consequently the boom or supporting arm 22 together with the drilling tool 1 may be swung laterally in either direction relative to the truck frame and thereafter rigidly held in position by the clamp mechanism 93, 95, 96. It is therefore obvious that the drilling tool may be positioned

at either rib or in any intermediate position across the coal face. The mechanism for rocking the tilting frame 14 about its axis relative to the truck frame comprises a worm gear segment 97 rigidly fixed by screws 98 to the casing 14. Meshing with this worm gear segment is a worm 99 formed integral with a shaft 100 rotatably mounted in ball bearings 101 suitably carried by an upstanding housing member 102 herein formed integral with one of the side members 5 of the truck frame. The worm 99 is adapted to be rotated by means of an operating handle 103. Interposed between the worm 99 and the handle 103 is a releasable positive lock 104 comprising a toothed clutch member 105 fixed to the shaft 106 to which the handle 103 is secured, this shaft being slidably mounted at its inner end in a bore 107 formed within the shaft 100. The teeth of the clutch member 104 are engageable with teeth 108 formed on a plate 109 bolted to the stationary housing 102. The adjacent end of the shaft 100 has formed thereon clutch teeth 110 which at all times cooperate with the teeth of the clutch member 105. Interposed between the clutch member 105 and a cap member 111 and surrounding the shaft 106 is a coil spring 112 which normally maintains the teeth of the clutch member 105 in engagement with the locking teeth 108. It is accordingly evident that when the parts are in the position shown in Fig. 6 the worm shaft 100 is positively locked to the housing 102. When it is desired to rotate the worm the operator grasps the handle 103 and slides the shaft 106 outwardly against the tension of the coil spring thereby releasing the teeth of the clutch member 105 from the teeth 108. The teeth 110 on the shaft 100 are still in engagement with the teeth of the clutch member and therefore upon rotation of the shaft 106 the worm 99 is rotated swinging the worm gear 97 together with the tiltable housing 14, relative to the truck frame. As a result the supporting column 16, the boom 22 and the drilling tool 1 may be rocked about a transverse axis relative to the truck frame, thereby enabling the drilling tool to be positioned adjacent the top or bottom of the working face or in any intermediate position.

Electric current is supplied to the motor 21 through a conductor cable 113 (see Fig. 8) having lead wires 114 suitably connected to stationary contact rings 115 fixed to a cylindrical member 116. The member 116 is secured by screws 117 to a stationary frame 118 rigidly secured to the housing 18 carried at the top of the supporting column 16. Yieldably engaging the rings 115 are contact members 119 connected to the lead wires 120 of a conductor cable 121 wound upon a rotatable cable reel or drum 122. The drum 122 is journaled on roller bearings 123 suitably supported by the frame 118. As illustrated

the cable reel 122 is driven from the motor through the bevel pinion 32 and bevel gear 33 heretofore described. Meshing with the bevel gear 33 is a bevel gear 124 (see Figs. 5 and 8) fixed by a key 125 to a horizontal shaft 126 arranged coaxially within the reel. This shaft 126 is journaled at its opposite ends in ball bearings 127 suitably supported by the frame 118. Herein formed integral with the outer end of the shaft 126 is a spur pinion 128 which meshes with planetary gears 129 rotatably mounted at 130 on a rotatable plate 131. The planetary gears 129 mesh with the teeth of a stationary internal gear 132 fixed by screws 133 to the frame 118, this internal gear forming a support for one of the roller bearings 123 upon which the cable reel is rotatably mounted. The plate 131 carries friction discs or plates 134 disposed on opposite sides of a friction disc or plate 135 suitably fixed to a member 136 bolted to the cable reel. Engaging the outer friction disc 134 is a plate 137. The friction plates 134, 135 are normally held in frictional engagement by means of bolts 139 and coil springs 140 which yieldably force the plates 131 and 137 together. The plate 137 is adapted to be moved outwardly to release the friction clutch 134, 135 by means of a hand wheel 141 threadedly connected at 142 to the plate 137 and having its threaded portion abutting the outer surface of the plate 131. It will be obvious that when the hand wheel 141 is rotated the plates 131 and 137 are forced apart thereby releasing the frictional engagement of the plates 134, 135 and as a result the cable reel is disconnected from its driving connection. A usual controller box 143 is provided for controlling the motor 21. This controller box is supported on a projecting bracket 144 herein formed integral with the supporting column 16 and is braced at its upper end by a strap member 145 extending between the controller box casing and a detachable cap or plate 146 forming a part of the housing 18.

A braking device is provided for holding the truck wheels against rotation and herein comprises a brake drum 147 secured to the rear truck axle 8 and with which a contractible brake band 148 cooperates. The brake band 148 is provided with suitable operating means including a lever 149 pivotally mounted on the truck frame 4. A toothed segment 150 and latch 151 are employed for maintaining the lever 149 in its different adjusted positions. This brake is used to hold the truck wheels stationary during the drilling operation and to prevent too rapid movement of the apparatus when moving along an inclined trackway.

In the operation of the improved drilling tool the apparatus is propelled under its own power along the mine trackway by the motor 21 through the driving connections between the motor and the truck wheels as described

above. As the drilling apparatus moves forwardly along the trackway the cable reel 122 pays out the conductor cable 121 and when the apparatus moves rearwardly the conductor cable 121 is automatically wound in by the cable reel. The cable reel may be disconnected from the motor at will simply by releasing the frictional engagement of the clutch plates 134, 135. When the drilling apparatus reaches the working face the operator applies the brake 147 holding the truck wheels against rotation thereby maintaining the truck stationary. If it is desired to operate the drill at one side of the trackway or the other the operator releases the clamp 95 and swings the supporting column 16 about its axis relative to the truck frame thereby moving the supporting arm 22 and the drilling tool 1 to one side or the other of the longitudinal axis of the apparatus, for instance, 85 from the full line position shown in Fig. 3 to the dotted line position. If it is desired to swing the drilling tool upwardly or downwardly the operator releases the lock 105, 108 and rotates the worm 99 thereby swinging 90 the worm gear segment 97 together with the tiltable housing 14 about a transverse horizontal axis relative to the truck frame, for instance, from the full line position shown in Fig. 1 to the dotted line position. The worm 95 99 is thereafter locked against rotation by means of the positive lock 105, 108. The drilling tool may be swung bodily about the axis of the supporting arm or boom 22 by means of the worm gearing 65, 67. When 100 desired the angle of the drilling tool relative to the supporting arm 22 may be changed simply by releasing the clamping screw 52 and swinging the drilling tool bodily relative to the swivel bracket 39. It will be noted 105 that the truck wheels, drilling tool, and cable reel may be driven irrespective of the position of the motor 21 relative to the truck frame. It will further be noted that the motor 21 is so positioned on the frame 18 as to substantially counterbalance the weight of the drilling tool carried on the outer end of the boom and therefore due to such a counterbalanced arrangement of the tool it is possible to swing 110 the same in a vertical plane with facility. 115 When the drilling tool 1 is suitably positioned adjacent the working face the clutches 62 and 63 may be so controlled as to effect feeding movement of the drill bit 61 and after the hole is completed the drill bit may 120 be retracted from the face at a high speed all in the manner clearly described in the above mentioned copending applications.

As a result of this invention an improved self-propelled drilling apparatus is provided 125 whereby the drilling tool may assume a plurality of positions relative to the working face and by employing the improved supporting and adjusting means for the tool the latter may be moved into such positions with 130

facility and expeditiously. Furthermore it will be noted that by arranging the motor in the manner described the apparatus is rendered extremely well balanced, the weight of the motor counterbalancing the weight of the drilling tool. These and other uses and advantages of this invention will be clearly apparent to those skilled in this art.

While I have in this application specifically described one form which the invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a drilling apparatus, a wheeled support, an upright standard wholly supported thereby and tilttable relative thereto about a horizontal axis extending transversely of said support adjacent the bottom of said standard, a boom adjustably mounted at its rear end on and solely supported by said standard and rigidly held against swinging movement relative thereto, said boom extending forwardly in advance of said support substantially lengthwise of the apparatus, devices on said support and standard for swinging the latter about said axis and for holding the same in its different tilted positions, and a drilling tool carried by said boom at the forward extremity thereof.

2. In a drilling apparatus, a wheeled support, a frame mounted thereon and wholly supported thereby and tilttable relative thereto about a horizontal axis extending transversely of said support, a standard mounted on said frame for rotation about its longitudinal axis, a boom supported at its rear end on said standard and extending forwardly in advance of said support substantially lengthwise of the apparatus, and a drilling tool carried by said boom at the forward extremity thereof.

3. In a drilling apparatus, a wheeled support, a standard wholly supported thereby and mounted thereon for tilting movement about a horizontal axis extending transversely of said support and for rotation about its longitudinal axis, a boom supported at its rear end by said standard and extending forwardly in advance of said support substantially lengthwise of the apparatus, and a drilling tool carried by said boom at the forward extremity thereof.

4. In a drilling apparatus, a wheeled support, a standard mounted thereon for tilting movement relative thereto about a horizontal axis extending transversely of said support, a frame supported by said standard and rigidly held against swinging movement relative thereto, a motor carried by said frame, a boom mounted at its rear end on said frame

and solely supported by said frame and standard, said boom extending forwardly in advance of said support substantially lengthwise of the apparatus, a drilling tool carried by said boom at the forward extremity thereof, devices on said support and standard for swinging the latter about said axis and for holding the same in its different tilted positions, and driving connections between said motor and said drilling tool.

5. In a drilling apparatus, a wheeled support, a frame wholly supported by and pivotally mounted on said support to rock relative thereto on a transverse axis, a standard supported at its lower end on said tilttable frame for rotation relative thereto about an axis perpendicular to said first mentioned axis, a boom rotatably mounted on the upper end of said standard, and a drilling tool carried by said boom.

6. In a drilling apparatus, a wheeled support, a frame wholly supported by and pivotally mounted on said support to rock relative thereto on a transverse axis, a standard supported at its lower end on said tilttable frame for rotation relative thereto about an axis perpendicular to said first mentioned axis, a boom rotatably mounted on the upper end of said standard for rotation relative thereto about its longitudinal axis, and a drilling tool carried by said boom.

7. In a drilling apparatus, a wheeled support, a housing wholly supported by and pivotally mounted on said support for tilting movement relative thereto about a transverse axis, a standard rotatably mounted on said housing, a boom supported at its rear end by said standard and extending forwardly in advance of said support substantially lengthwise of the apparatus, and a drilling tool carried by the forward extremity of said boom.

8. In a drilling apparatus, a wheeled support, a housing wholly supported thereby and pivotally mounted thereon for tilting movement relative thereto about a transverse axis, a standard rotatably mounted on said housing, a boom journaled at its rear end on said standard for rotation relative thereto about its longitudinal axis and extending forwardly in advance of said support substantially lengthwise of the apparatus, and a drilling tool carried by said boom at the forward extremity thereof.

9. In a drilling apparatus, a wheeled support, a standard pivotally mounted thereon to rock relative thereto on a transverse axis, a motor carried by the upper end of said standard, a boom mounted at its rear end on and solely supported by said standard and rigidly held against swinging movement relative thereto, said boom extending forwardly in advance of said support substantially lengthwise of the apparatus, a drilling tool carried by said boom at the forward extrem-

- ity thereof, devices on said support and standard for swinging the latter about said axis and for holding the same in its different adjusted positions, and driving connections between said motor and said drilling tool.
10. In a drilling apparatus, a wheeled support, a standard pivotally mounted thereon to rock relative thereto on a transverse axis, a motor carried at the upper end of said standard, a boom mounted on said standard, a drilling tool carried by said boom, and driving connections between said motor and drilling tool and the wheels of said support.
11. In a drilling apparatus, a wheeled support, a tubular standard pivotally mounted thereon to rock on a transverse axis, a motor carried at the upper end of said standard, a boom mounted on said standard, a drilling tool carried by said boom, and driving connections between said motor and drilling tool and the wheels of said support, the driving connections between said motor and the wheels including a transmission element extending through said standard.
12. In a drilling apparatus, a wheeled support, a housing pivotally mounted on said support to rock relative thereto on a transverse axis, a standard mounted on said housing for rotation about its longitudinal axis, a frame carried at the upper end of said standard, a motor carried by said frame, a boom mounted on said frame and arranged in axial alinement with the motor, and a drilling tool carried by said boom and driven by said motor.
13. In a drilling apparatus, a wheeled support, a housing supported thereon for tilting movement about a transverse axis, an upwardly extending supporting column rotatably mounted on said housing for rotation about its longitudinal axis, a frame supported at the upper end of said column, a motor carried by said frame, a boom rotatably mounted on said frame about its longitudinal axis, the axis of said boom coinciding with the motor axis, a drilling tool pivotally mounted on said boom, and driving connections between the motor and said drilling tool.
14. In a drilling apparatus, a wheeled support, a housing supported thereon for tilting movement about a transverse axis, an upwardly extending supporting column rotatably mounted on said housing for rotation about its longitudinal axis, a frame supported at the upper end of said column, a motor carried by said frame, a boom rotatably mounted on said frame about its longitudinal axis, the axis of said boom coinciding with the motor axis, a drilling tool pivotally mounted on said boom, and driving connections between the motor and said drilling tool and the wheels of said support.
15. In a drilling apparatus, a wheeled support, a housing supported thereon for tilting movement about a transverse axis, an upwardly extending tubular supporting column rotatably mounted on said housing for rotation about its longitudinal axis, a frame supported at the upper end of said column, a motor carried by said frame, a boom rotatably mounted on said frame about its longitudinal axis, the axis of said boom coinciding with the motor axis, a drilling tool pivotally mounted on said boom, and driving connections between the motor and said drilling tool and the wheels of said support, the driving connections between said motor and the wheels including a transmission elements extending through said column.
16. In a drilling apparatus, a wheeled support, an upstanding column mounted on said support to rock relative thereto on a transverse axis, a frame supported at the upper end of said column, a motor carried by said frame, a drilling tool supported by said frame, and driving connections between said motor and the drilling tool and the wheels of said support.
17. In a drilling apparatus, a wheeled support, a housing pivotally mounted thereon to rock relative thereto on a transverse axis, an upstanding column supported on said housing for rotation relative thereto about its longitudinal axis, a motor supported by said column, a drilling tool supported by said column, and driving connections between said motor and said drilling tool and the wheels of said support.
18. In a drilling apparatus, a wheeled support, a housing supported thereon for pivotal movement about a transverse horizontal axis, an upstanding column supported on the housing for rotation about its longitudinal axis, a casing carried at the upper end of said column, a motor secured to said casing, a forwardly projecting supporting arm rotatably mounted on said casing about its longitudinal axis, the axes of said supporting arm and motor being arranged in alinement, mechanism for rotating said supporting arm relative to said casing, a drilling tool pivotally mounted on the outer extremity of said supporting arm, driving connections between said motor and said drilling tool, and driving connections between said motor and the wheels of said support.
19. In a drilling apparatus, a wheeled support, a housing supported thereon for tilting movement about a transverse horizontal axis, an upstanding column mounted on said housing for rotation about its longitudinal axis, a casing supported on the upper end of said column, said casing having a rearwardly projecting portion, a motor carried by said rearwardly projecting portion, a forwardly projecting supporting arm rotatably mounted on said casing for rotation about its longitudinal axis, said arm being arranged in axial alinement with said motor, mechanism for rotating said arm relative to said

- casing, a drilling tool pivotally mounted on the outer extremity of said arm, driving connections between said motor and said drilling tool, and driving connections between said motor and the wheels of said support.
20. In a drilling apparatus, a wheeled support, a frame wholly supported thereon and adjustable relative thereto about a transverse axis, a boom adjustably mounted on said frame, a drilling tool carried at the outer end 10 of said boom, mechanism for driving said drilling tool including a driving motor at the end of said boom remote from said tool and supported by said frame for adjustment therewith relative to said support, and mechanism driven by said motor operative irrespective of the position of said boom relative to said support for driving the wheels of said support.
21. In a drilling apparatus, a wheeled support, a frame mounted thereon for rotation relative thereto about a vertical axis, a boom adjustably mounted on said frame for movement relative thereto, a drilling tool swiveled on the outer extremity of said boom, a motor at the end of said boom remote from said drilling tool and supported by said frame for rotation therewith relative to said support, driving connections between said motor and said drilling tool, and mechanism 20 driven by said motor operative irrespective of the position of said boom relative to said support for driving the support wheels.
22. In a drilling apparatus, a wheeled support, a frame mounted thereon for tilting movement relative thereto about a transverse axis, a column rotatably mounted on said frame for rotation relative thereto about its longitudinal axis, a motor carried by said column, a boom carried by said column and 30 adjustable relative thereto, a drilling tool swiveled on the outer extremity of said boom, and driving connections between said motor and said drilling tool.
23. In a drilling apparatus, a wheeled support, a frame mounted thereon for tilting movement relative thereto about a transverse axis, a column rotatably mounted on said frame for rotation relative thereto about its longitudinal axis, a motor carried by said column, a boom carried by said column and adjustable relative thereto, a drilling tool swiveled on the outer extremity of said boom, driving connections between said motor and 40 said drilling tool, and driving connections between said motor and the wheels of said support.
24. In a drilling apparatus, a wheeled support, a frame mounted thereon for rotation about a vertical axis, a boom carried by said frame and adjustable angularly relative to said support, said boom being rotatably mounted on said frame for rotation relative thereto about its longitudinal axis, a drilling tool adjustably mounted on the outer ex- 50 tremity of said boom, a motor on said support and mounted on said frame for rotation therewith relative to said support, driving connections between said motor and said drilling tool, and constantly operative driving connections between said motor and the wheels of said support.
25. In a drilling apparatus, a wheeled support, a frame mounted thereon for rotation about a vertical axis, a boom carried by said frame and rotatable relative thereto about its longitudinal axis, a drilling tool adjustably mounted on the outer extremity of said boom, a motor carried by said rotatable frame and adjustable therewith relative to said support, driving connections between said motor and said drilling tool, and constantly operative driving connections between said motor and the wheels of said support.
26. In a drilling apparatus, a wheeled support, a frame thereon, a boom pivotally mounted between its ends on said frame, a motor carried by said boom at one end thereof and adjustable therewith, a drilling tool carried at the other end of said boom, driving connections between said motor and said tool, and driving connections between said motor and the support wheels including a transmission element having its axis coincident with the pivotal axis of said boom.
27. In a drilling apparatus, a wheeled support, a frame thereon, a boom pivotally mounted between its ends on said frame for tilting movement in different planes about a plurality of axes, a motor carried by said boom at one end thereof and adjustable therewith, a drilling tool carried at the other end of said boom, driving connections between said motor and said tool, and driving connections between said motor and the support wheels including transmission elements having their axes coincident with the pivotal axes of said boom.
28. In a drilling apparatus, a portable wheeled support, an upstanding frame on said support, a boom pivotally mounted intermediate its ends on said upstanding frame for swinging movement in intersecting planes, a motor carried at one end of said boom and adjustable therewith during swinging of the latter, a drilling tool carried at the other end of said boom, driving connections between said motor and said drilling tool, and driving connections between said motor and the support wheels operative to propel said support irrespective of the adjusted position of said boom relative thereto.
29. In a drilling apparatus, a wheeled support, a frame mounted thereon, a boom pivotally mounted intermediate its ends on said frame, a motor carried at one end of said boom and adjustable therewith, a drilling tool carried at the other end of said boom, driving connections between said motor and said drilling tool, and driving connections

- between said motor and the support wheels for propelling the apparatus irrespective of the adjusted position of said boom relative to said support.
30. In a drilling apparatus, a wheeled support, a column pivotally connected at its lower end to said support for swinging movement relative to said support about a transverse axis, a frame carried at the upper end of said column, a motor carried by said frame, a boom adjustably mounted at its inner end on said frame, a drilling tool swiveled on the outer extremity of said boom, and driving connections between said motor and said drilling tool.
31. In a drilling apparatus, a wheeled support, a frame mounted thereon and tiltable relative thereto about a transverse horizontal axis, mechanism for tilting said frame relative to said support, a standard rotatably mounted on said tilttable frame, means for securing said standard to said tilttable frame, a frame carried on the upper end of said standard and carrying a motor, a boom rotatably mounted on said last mentioned frame about its longitudinal axis, mechanism for rotating said boom relative to said frame, a drilling tool swiveled on the outer extremity of said boom, and driving connections between said motor and said drilling tool.
32. In a drilling apparatus, a wheeled support, a frame mounted thereon and tilttable relative thereto about a transverse horizontal axis, mechanism for tilting said frame relative to said support, a standard rotatably mounted on said tilttable frame, means for securing said standard to said tilttable frame, a frame carried on the upper end of said standard and carrying a motor, a boom rotatably mounted on said last mentioned frame about its longitudinal axis, mechanism for rotating said boom relative to said frame, a drilling tool swiveled on the outer extremity of said boom, driving connections between said motor and said drilling tool, and driving connections between said motor and the wheels of said support operative to propel said support in any adjusted position of said standard relative thereto.
33. In a drilling apparatus, a wheeled support, a frame mounted thereon and wholly supported thereby and tilttable relative thereto about a transverse horizontal axis, mechanism for tilting said frame relative to said support, a second frame mounted on said tilttable frame for rotation about a vertical axis, means for securing said second frame to said tilttable frame, a boom mounted on said second frame, and a drilling tool adjustably mounted on the outer extremity of said boom.
34. In a drilling apparatus, a wheeled support, a standard mounted thereon for tilting movement relative thereto about a horizontal axis extending transversely of said support, a frame supported by said standard, a motor carried by said frame, a boom mounted at its rear end on said frame and extending forwardly in advance of said support substantially lengthwise of the apparatus, a drilling tool carried by said boom at the forward extremity thereof and mounted thereon for adjustment bodily about the boom axis into different parallel positions, and driving connections between said motor and said drilling tool.
35. In a drilling apparatus, a wheeled support, a standard mounted thereon for tilting movement relative thereto about a horizontal axis extending transversely of said support, a frame supported by said standard, a motor carried by said frame, a boom mounted at its rear end on said frame and extending forwardly in advance of said support substantially lengthwise of the apparatus, a drilling tool carried by said boom at the forward extremity thereof and mounted thereon for adjustment bodily about the boom axis into different parallel positions and for adjustment about an axis perpendicular to the boom axis, and driving connections between said motor and said drilling tool.
36. In a drilling apparatus, a support, a frame mounted thereon for tilting movement relative thereto about a transverse axis, a boom mounted at its rear end on and solely supported by said frame and rigidly held against swinging movement relative thereto, said boom extending forwardly in advance of said support, a drilling tool mounted on the outer extremity of said boom, a rotary motor supported by said frame and having its axis alined with the boom axis, devices on said support and frame for swinging the latter about said axis for holding the same in its different tilted positions, and driving connections between said motor and said drilling tool.
37. In a drilling apparatus, a support, a frame mounted thereon for tilting movement relative thereto about a transverse axis, a boom mounted at its rear end on said frame for rotation about its longitudinal axis and extending forwardly in advance of said support, a drilling tool mounted on the outer extremity of said boom and adjustable therewith about the boom axis, a rotary motor supported by said frame and having its axis alined with the boom axis, and driving connections between said motor and drilling tool operative to drive the latter irrespective of the position thereof about said boom axis.
38. In a drilling apparatus, a portable support, an elongated supporting structure wholly supported by and adjustably mounted on said support and extending a substantial distance in advance of said support, a drilling tool adjustably mounted on the outer extremity of said supporting structure, said supporting structure being adjustable to position said drilling tool in a plurality of rela-

tively high and relatively low parallel planes and into positions at either side of said support, a motor, mechanism driven by said motor for driving the drilling tool, and power supply apparatus mounted on said supporting structure and including a power conductor reel driven by said motor.

39. In a drilling apparatus, a portable support, a frame wholly supported by and pivotally mounted on said support to rock relative thereto on a transverse axis, a second frame mounted on said tiltable frame for rotation relative thereto about an axis perpendicular to said first mentioned axis, an elongated supporting structure adjustably mounted on said second frame and extending a substantial distance in advance of said support, a drilling tool adjustably mounted on the outer extremity of said supporting structure, said supporting structure and frames being adjustable to position said drilling tool in a plurality of relatively high and relatively low parallel planes and into positions at either side of said support, a motor, and mechanism driven by said motor for driving said drilling tool.

40. In a drilling apparatus, a portable support, a frame wholly supported by and pivotally mounted on said support to rock relative thereto on a transverse axis, a second frame mounted on said tiltable frame for rotation relative thereto about an axis perpendicular to said first mentioned axis, an elongated supporting structure adjustably mounted on said second frame and extending a substantial distance in advance of said support, a drilling tool adjustably mounted on the outer extremity of said supporting structure, said supporting structure and frames being adjustable to position said drilling tool in a plurality of relatively high and relatively low parallel planes and into positions at either side of said support, a motor, mechanism driven by said motor for driving said drilling tool, and mechanism driven by said motor for propelling the apparatus.

41. In a drilling apparatus, a support, a frame mounted thereon for tilting movement about a transverse axis, a swivel frame mounted on said tiltable frame for rotation about a vertical axis, a boom mounted at its rear end on said swivel frame and extending forwardly in advance of said support, a drilling tool mounted on the outer extremity of said boom, a rotary motor supported by said swivel frame and having its axis alined with the boom axis, and driving connections between said motor and said drilling tool.

42. In a drilling apparatus, a support, a frame mounted thereon for tilting movement about a transverse axis, a swivel frame mounted on said tiltable frame for rotation about a vertical axis, a boom mounted at its rear end on said swivel frame for rotation about its longitudinal axis and extending

forwardly in advance of said support, a drilling tool mounted on the outer extremity of said boom and adjustable therewith about the boom axis, a rotary motor supported by said swivel frame and having its axis alined with the boom axis and driving connections between said motor and said drilling tool operative to drive the latter irrespective of the position thereof about said boom axis.

43. In a drilling apparatus, a support, a frame mounted thereon for tilting movement about a transverse axis, a swivel frame mounted on said tiltable frame for rotation about a vertical axis, a boom mounted at its rear end on said tiltable frame and extending forwardly in advance of said support, a drilling tool mounted on the outer extremity of said boom, a rotary motor supported by said tiltable frame and having its axis alined with the boom axis, driving connections between said motor and said drilling tool, and mechanism driven by said motor propelling the apparatus.

44. In a drilling apparatus, a support, a frame mounted thereon for tilting movement about a transverse axis, a swivel frame mounted on said tiltable frame for rotation about a vertical axis, a boom mounted at its rear end on said tiltable frame for rotation about its longitudinal axis and extending forwardly in advance of said support, a drilling tool mounted on the outer extremity of said boom and adjustable therewith about the boom axis, a rotary motor supported by said tiltable frame and having its axis alined with the boom axis, driving connections between said motor and said drilling tool operative to drive the latter irrespective of the position thereof about said boom axis, and mechanism driven by said motor for propelling the apparatus.

45. In a drilling apparatus, a wheeled support, an upright standard supported thereby and tiltable relative thereto about a horizontal axis extending transversely of said support and arranged adjacent the lower end of said standard, a boom adjustably mounted at its rear end on said standard and extending forwardly in advance of said support substantially lengthwise of the apparatus, and a drilling tool carried by said boom at the forward extremity thereof and adjustable angularly relative to said boom to drill holes in relatively inclined planes.

46. In a drilling apparatus, a wheeled support, a standard mounted thereon for tilting movement relative thereto about a horizontal axis extending transversely of said support, a frame supported by said standard, a motor carried by said frame, a boom mounted at its rear end on said frame and extending forwardly in advance of said support substantially lengthwise of the apparatus, a drilling tool carried by said boom at the forward extremity thereof and adjustable angularly

relative to said boom to drill holes in relatively inclined planes, and driving connections between said motor and said drilling tool.

47. In a drilling apparatus, a wheeled support, a standard pivotally mounted thereon to rock relative thereto on a transverse axis, a motor carried by the upper end of said standard, a boom mounted at its rear end on said standard and extending forwardly in advance of said support substantially lengthwise of the apparatus, a drilling tool carried by said boom at the forward extremity thereof and adjustable angularly relative to said boom to drill holes in relatively inclined planes, and driving connections between said motor and said drilling tool.

48. In a drilling apparatus, a support, a frame mounted thereon for tilting movement relative thereto about a transverse axis, a boom mounted at its rear end on said frame and extending forwardly in advance of said support, a drilling tool mounted on the outer extremity of said boom and adjustable angularly relative thereto to drill holes in relatively inclined planes, a rotary motor supported by said frame and having its axis alined with the boom axis, and driving connections between said motor and said drilling tool.

50 In testimony whereof I affix my signature.
MORRIS P. HOLMES.

CERTIFICATE OF CORRECTION.

Patent No. 1,866,932.

July 12, 1932.

MORRIS P. HOLMES.

It is hereby certified that error appears in the printed specification of the above numbered patent requiring correction as follows: Page 3, line 54, after "drum" insert 96; page 6, line 78, claim 15, for "elements" read element; and page 9, line 87, claim 43, before "propelling" insert the word for; and that the said Letters Patent should be read with these corrections therein that the same may conform to the record of the case in the Patent Office.

Signed and sealed this 30th day of October, A. D. 1934.

relative to said boom to drill holes in relatively inclined planes, and driving connections between said motor and said drilling tool.

47. In a drilling apparatus, a wheeled support, a standard pivotally mounted thereon to rock relative thereto on a transverse axis, a motor carried by the upper end of said standard, a boom mounted at its rear end on said standard and extending forwardly in advance of said support substantially lengthwise of the apparatus, a drilling tool carried by said boom at the forward extremity thereof and adjustable angularly relative to said boom to drill holes in relatively inclined planes, and driving connections between said motor and said drilling tool.

48. In a drilling apparatus, a support, a frame mounted thereon for tilting movement relative thereto about a transverse axis, a boom mounted at its rear end on said frame and extending forwardly in advance of said support, a drilling tool mounted on the outer extremity of said boom and adjustable angularly relative thereto to drill holes in relatively inclined planes, a rotary motor supported by said frame and having its axis alined with the boom axis, and driving connections between said motor and said drilling tool.

50 In testimony whereof I affix my signature.
